UNITED STATES PATENT OFFICE.

JACOB A. HYLE, OF PHILADELPHIA, AND JACOB W. HERMAN, OF HARRISBURG, PENNSYLVANIA, ASSIGNEES TO NATIONAL STEEL TIE COMPANY, OF HARRISBURG, PENNSYLVANIA, A CORPORATION OF DELAWARE.

RAILWAY-TIE AND RAIL-FASTENING.

1,108,370.

Specification of Letters Patent. Patented Aug. 25, 1914.

Application filed December 2, 1913. Serial No. 804,212.

To all whom it may concern:

Be it known that we, JACOB A. HYLE and JACOB W. HERMAN, citizens of the United States, residing at Philadelphia and Harrisburg, respectively, and State of Pennsylvania, have invented certain new and useful Improvements in Railway-Ties and Rail-Fastenings, of which the following is a specification.

10 Our invention relates to the construction of railway ties and means for firmly and securely fastening the track rails in proper position on the ties of steam and electric railways.

15 The main object of this invention is to provide an improved railway tie constructed of metal which may be filled with asphaltum and coarse stone or concrete, or a creosote coated wooden block may be inserted within 20 each end of the tie and located beneath the base of each track rail, in connection with simple, economical, strong, durable and efficient means for rigidly securing the track rails to said improved railway tie.

25 Another object of the invention is to furnish novel securing means for firmly fastening the track rails to our improved tie, and means for the insulation of the track rails from said tie.

30 A further object is to provide novel means for receiving the side thrust of the track rails, and means for regaging the track rails to the railway tie.

The foregoing and such other objects as 35 may occur from the ensuing description, are attained by the means hereinafter more fully described, and by the combination, construction, arrangement and location of the parts such as illustrated in the accompanying drawings, and particularly set forth in the claims appended hereto.

Reference now being had to the accompanying drawings which form a part of this specification and in which similar numerals 45 of reference indicate like parts throughout the several views, it will be seen that: Figure 1, is a view partly in side elevation and partly in section on the line 1—1. Fig. 2, illustrating the improved tie and fastening 50 means embodying our invention. Fig. 2, is a longitudinal sectional view through the tie and track rail securing means, showing the track rails in cross-section. Fig. 3, is a plan view of our improved railway tie. Fig. 4, is

55 a plan view of the tie and track rail securing means, showing the track rails secured to the tie. Fig. 5, is a perspective view of the metal plate secured within the tie. Fig. 6, is a perspective view of the metal plate which rests on the upper portion of the tie and beneath the base of the track rail. Fig. 7, is a perspective view of the insulating pad or cushion which rests on the upper surface of the tie beneath the base of the track rail. Fig. 8, is a perspective view of the insulating pad or plate secured within the tie. Fig. 9, is a perspective view of an insulating fibrous sleeve adapted to surround the upper portion of all of the rivet bolts. Fig. 10, is a side view of one of the rivet bolts and nuts 65 for securing the inside plates to the tie. Fig. 11, is a side view of one of the track rail securing bolts and nuts. Fig. 12, is a top plan view of one of the rivet bolts shown in Fig. 10. Fig. 13, is a perspective 75 view of the insulating fibrous washer located beneath the head of all of the rivet bolts; and Fig. 14, is a perspective view of one of the track rail securing clips.

In carrying out our invention we provide 80 a railway tie of suitable dimensions throughout its length and breadth and the metallic portion of said tie with which our invention is embodied in the form illustrated in the drawings, comprises a metallic shell 85 1 of any suitable or desirable metal having a flattened upper portion and base portion and rounded side portions 2, as clearly shown in Fig. 1 of the drawings.

The upper surface of the tie near each 90 end thereof is provided with a circular opening 3 and elongated openings 4 extending from either side of said opening 3 and connected therewith, and perforations 5 adapted to receive the securing bolts hereinafter described.

Upon the upper surface of the tie directly beneath the base of the track rails 6 is placed a resilient pad or cushion 7 of insulating material made up of a number of thicknesses of any suitable material, thereby forming an insulating cushion for the rail and serving to prevent a rail from breaking when subjected to the strain and pounding of the rolling stock. 100 This cushion or pad 7 is covered with a metallic wear plate 8 located beneath the base 105 of the rail to receive the motion of the rail,

and to prevent wear on the pad or cushion, and said plate is rolled from any suitable metal and made to assume the shape such as shown in Fig. 6, having upward integral projections or lugs 9 and 9' formed near each end thereof, the base of the rail resting between the lugs or projections, said lugs or projections being adapted to contact with the sides of the base of the rail and take up any side thrust to which the rail may be subjected, and said plate having a recess 10 formed between the projections or lugs near each end thereof to receive the track rail securing clips 11, and openings 12 for the securing bolts. This plate 8 also serves as a means for regaging the track rails as will hereafter be more fully described.

Against the inner upper surfaces of the longitudinal central portion, near each end of the tie is placed a pad or plate of insulating material 13, having openings therethrough for receiving the securing bolts and directly beneath said pad or plate 13 and in contact therewith is a metal plate 14, having corresponding openings therethrough, both the insulating plate and metal plate being secured to the inner upper portion of the tie by means of threaded rivet bolts 15 having sealing nuts 16 fitted thereto, said bolts each being provided with a head 17 having flat or vertical sides 18, adapted to receive a wrench for manipulating the removal of the bolt, and between said head 17 and the upper surface of the tie is placed an insulating fiber washer 19, the stem of the bolt being surrounded by a sleeve 20 of insulating fiber extending through the upper portion of the tie, and the flat or vertical side of the head of said bolt 15 resting in contact with the end portion of the plate 8 and the outer end portion of the rail securing clip, thus serving as an additional means for taking the side thrust of the said plate and clip when subjected to the side thrust of the track rail when under strain.

If desired, a wooden block 21, may be placed within the tie near each end thereof directly beneath the base of the track rail, said block being provided with a central longitudinal recess adapted to receive the plates 13 and 14. This block may be made with straight side walls, as shown, or it may be made with rounded sides to fit snugly within the tie, or the tie may be entirely filled with asphaltum or concrete, all as clearly shown in Fig. 1 of the drawings, the said block and concrete both serve to prevent the tie from being crushed down beneath the base of the rail.

As shown in Fig. 11 of the drawings, the stem of each of the track rail securing bolts 22 is provided with a rounded threaded portion 23 adapted to receive a securing nut 24 and a reduced portion 25 with a large rounded shaped head 26.

Each rail securing clip 11 is formed by a steel plate having a downward projecting rear portion 11', the body portion extending inward within the space 10 of the wear plate 8, and the projections 9 and 9' serving to prevent the clips from turning, said clips having an upward and forwardly extending inner end terminating in the inclined overlapping portion 27 adapted to contact with and securely clamp the upper surface of the base of the track rail. This form of clip will furnish resiliency and serve as a spring lock for the securing nut, since the body portion is out of contact with the wear plate 8, and the rear portion of the clip will rest in contact with the vertical or flattened head portion 18 of the bolt 15.

The track rail securing bolts are adjusted into the position clearly shown in Fig. 2 by passing the large rounded head portion downward through the circular opening 3 in the tie, the insulating pad or plate 13, and the metal plate 14 within the tie until the head is passed through the metal plate within the tie, then move the bolt sidewise until it reaches the outer end of the elongated opening, with the reduced portion 25 resting within the elongated opening in the metal plate 14, and the head portion 26 projecting below and in contact with the lower surface of said plate 14, whereby the accidental withdrawal of the bolt is prevented, the upper cylindrical portion of the bolt is passed through the perforations in the insulating pad or cushion 7 and the wear plate 8, and the rail securing clip 11 secured by a nut to the threaded end of the bolt, thus firmly securing the track rails to the tie.

It will be seen by reference to Fig. 6 that the wear plate 8 is adapted to serve as a regaging plate for the track rail, since it will be perceived that the plate is provided with projections or lugs 9 and 9', the projections 9' being slightly closer to the end of the plate on the outside of the rail than the projections 9 on the inside, hence when it is desired to regage the rail it is simply necessary to reverse the plate end for end thereby placing the projections 9 on the outside of the rail and the projections 9' on the inside, which will serve the purpose of suitably regaging the rails, and on curves where the rails may have worn off on the inside to a greater extent than that provided for in one plate, then it will simply be necessary to also reverse the plate on the opposite end of the tie in the manner hereinbefore described, thus insuring a greater and suitable degree of regagement of the rails.

It will be readily understood that the insulating pad or cushion located on top of the tie; the insulating plate secured within the tie, and the insulating fiber washer and sleeve herein described, will insure the

proper insulation of the track rails from the tie.

It will be obvious that slight changes may be resorted to in the details of the construction without departing from the spirit of our invention.

Having thus described our invention what we claim and desire to secure by Letters Patent is:—

10. 1. A metallic railway tie comprising, a metal shell having upper and lower flattened portions and rounded side portions, and provided with a circular opening and an elongated opening extending from either side of and connecting with said central opening near each end of the tie, a plate of insulating fiber and a metallic plate secured centrally within the tie against its inner upper surface.

20. 2. A metallic railway tie comprising, a metal shell having upper and lower flattened portions and rounded side portions, and provided with a circular opening and an elongated opening extending from either side of and connecting with said central opening near each end of the tie, a plate of insulating fiber and a metallic plate secured centrally within the tie against its inner upper surface, and a bolt and nut for firmly securing said plates within the tie, said bolt having a head provided with flattened sides, substantially as described and for the purpose set forth.

30. 3. A metallic railway tie comprising, a metal shell having upper and lower flattened portions and rounded side portions, and provided with a circular opening and an elongated opening extending from either side of and connecting with said central opening near each end of the tie, a plate of insulating fiber and a metallic plate secured within the tie against its inner upper surface, track rails, and means for securing said track rails and plates to the tie.

40. 4. A metallic railway tie comprising, a metal shell having upper and lower flattened portions and rounded side portions, a plate of insulating fiber and a metallic plate secured within the tie against its inner upper surface, track rails, and rail securing means consisting of a metal plate located on top of the tie, said plate having upward projections near each end thereof and a recess between said projections, securing bolts passing through said plate and through and within the tie, and rail securing clips fastened by said bolts to the upper face of said plate and within said recesses formed between the projections.

50. 5. A metallic railway tie comprising, a metal shell having upper and lower flattened portions and rounded side portions, a slotted metallic plate secured within the tie, a plate of insulating material secured within the tie between its inner upper surface and said

slotted metallic plate, a metal plate resting on the upper face of the tie, said plate being provided with upwardly extended projections and a recess formed between said projections, and means substantially as described for securing the track rails to the tie.

6. A metallic railway tie comprising, a metal shell having upper and lower flattened portions and rounded side portions, track rails, and rail securing means consisting of a metal plate located on the top of the tie, said plate having upwardly extending projections near each end thereof and a recess formed between said projections, and securing bolts and clips for firmly securing the track rails and the metal plate to the tie, said clips resting within said recesses.

7. A metallic railway tie comprising, a metal shell having upper and lower flattened portions and rounded side portions, a slotted metallic plate secured within the tie, a plate of insulating material secured within the tie between the inner upper surface of the tie and said metallic plate, track rails, and rail securing means consisting of a plate having upwardly extending projections near each end thereof and a recess formed between said projections, securing bolts passing through said plate and through the plates within the tie, and rail securing clips fastened by said bolts to the upper face of said plate and resting within said recesses.

8. A metallic railway tie comprising, a metal shell having upper and lower flattened portions and rounded side portions, track rails, and rail securing and regaging means consisting of a metal plate located on top of the tie, said plate having upwardly extended projections formed near each end thereof, the projections being located nearer one end than at the other end, and a recess formed near each end between said projections, and securing bolts and clips for firmly securing the track rails and the metal plate to the tie.

9. A metallic railway tie comprising, a metal shell having upper and lower flattened portions and rounded side portions, track rails, a slotted metallic plate secured within the tie, a plate of insulating material secured within the tie between the inner upper surface of the tie and said metallic plate, and rail securing and regaging means consisting of a metal plate located on top of the tie, said plate having upwardly extending projections formed near each end thereof, the projections being more remote from one end than from the other end and a recess formed between each set of projections, and securing bolts and clips for firmly securing the track rails and said metal plates to the tie.

10. A metallic railway tie comprising, a metal shell having upper and lower flattened

portions and rounded end portions, a solid filling within the shell, track rails, and rail securing means consisting of a metal plate having upwardly extended projections formed near each end thereof, and a recess formed near each end between said projections, a clip secured within each recess and to the upper surface of the base of the rail, and securing bolts having a reduced stem portion and rounded head adapted to pass through the tie, the headed portion resting within the tie, and a threaded outer end portion to which is fitted a nut for securing the said clips and metal plate to the track rail and tie.

11. A metallic railway tie comprising, a metal shell having upper and lower flattened portions and rounded side portions, a slotted metallic plate secured within the tie, a plate of insulating material secured within the tie between the inner upper sur-

face of the tie and said slotted metallic plate, a wooden block secured within the tie near each end thereof, track rails, and rail securing means consisting of a metal plate resting on top of the tie beneath the base of the rail, said plate having upwardly extending projections formed near each end thereof and a central recess formed between each set of projections, securing bolts passing through said plate and tie and the plates within the tie, rail fastening clips, and a securing nut fitted to the threaded end of the bolt for securing the clip within said recess and over the base of the track rail.

In testimony whereof we affix our signatures in presence of two witnesses.

JACOB A. HYLE.

JACOB W. HERMAN.
